(57) **CLAIM**

The ornamental design for a building anchor, as shown and described.

DESCRIPTION

1.-6. Building Anchor

Figure 1.1 is a perspective view of our new design for a building anchor.

Figure 1.2 is a front side elevation view of Figure 1.1.

Figure 1.3 is a back side elevation view of Figure 1.1.

Figure 1.4 is a left side elevation view of Figure 1.1.

Figure 1.5 is a top side plan view of Figure 1.1.

Figure 1.6 is a bottom side plan view of Figure 1.1.

Figure 1.7 is an enlarged view of Figure 1.5.
